(57) **CLAIM**

The ornamental design for a mobile bar as shown and described.

DESCRIPTION

FIG. 1 is a top perspective view of a mobile bar showing the new design;

FIG. 2 is a back perspective view thereof;

FIG. 3 is a front view thereof;

FIG. 4 is a back view thereof;

FIG. 5 is a right view thereof;

FIG. 6 is a left view thereof; and,

FIG. 7 is a top view thereof.

The broken lines shown in the figures illustrate portions of the mobile bar that form no part of the claimed design.
